UNITED STATES PATENT OFFICE.

OSCAR ONSRUD, OF CHICAGO, ILLINOIS.

CORE-DRUM.

1,090,492.

Specification of Letters Patent. Patented Mar. 17, 1914.

Application filed May 12, 1913. Serial No. 767,053.

To all whom it may concern:

Be it known that I, OSCAR ONSRUD, a citizen of the United States of America, and a resident of Chicago, county of Cook, and 5 State of Illinois, have invented certain new and useful Improvements in Core-Drums, of which the following is a specification.

This invention relates to contractible cores employed in casting in general, and more 10 particularly to casting in metal cylindrical objects such as pipes.

The main objects of the invention are to provide a core drum of improved design and which may be prepared for use and operated 15 with comparative rapidity and with little expense and waste of material.

An illustrative embodiment of this invention is shown in the accompanying drawings, in which:

20 Figure 1 is a longitudinal sectional view partly broken away of a core drum constructed according to this invention. Fig. 2 is an end view of the core drum. Fig. 3 shows details of spacing blocks employed 25 in the construction.

It is desirable to have core drums so constructed that they may be contracted for the purpose of permitting their removal from 30 castings, or that they may contract when the castings are cooling by pressure received from the latter.

Referring to the drawings, a sheet of metal 1 is shown by way of example in the form of a cylinder having its edges 2 and 35 3 overlapping to form an expansion joint, so that the cylinder may be expanded or contracted. Welded to the inner surface of the cylinder are T-bars 4 having pivotal connections 5 with a plurality of pairs of toggle 40 arms 6. The inner ends of the toggle arms are pivoted by bolts 8 to angle bars 9 extending throughout the length of the cylinder. The bars 9 are secured together by bolts 10 passing through the said bars and 45 spacing blocks 11. Rigid with the angle bars 9 and spacing blocks 11 are a pair of shafts 12 and 13. The shaft 12 is provided with a square head 14 by means of which the core may be rotated, for the purpose of 50 equally distributing loam around the cylinder 1 by means of a sweep. When thus rotated the cylinder 1 is supported in a horizontal position by being suitably journaled at the shafts 12 and 13.

55 It will be seen that the shafts 12 and 13

and the angle bars 9 comprise a rigid unit which may be shifted longitudinally of the cylinder 1, while the toggles 6 swing from their pivotal connections 5 with the T-bars 4. This longitudinal movement of the core 60 bars will cause the diameter of cylinder 1 to be varied, but such movement may be prevented, when the metal is being poured, by a link or lock bar 15 pivoted to one of the toggles 6 by a pin 16, and to one of the 65 bars 9 by a pin 17. The pin 17 is removable, thus a relative movement between the toggles 6 and core bars may be permitted or not, as desired. One or more of the bars 9 is provided with a clevis 18 to which a hook 70 may be attached for the purpose of contracting the core and lifting it out of the mold. Pin 17 may be made of wood or other soft material easily sheared by the contraction of the core drum upon the cooling and 75 contraction of the casting. In this way possible damage to the core or casting is prevented upon failure to remove the core before cooling of the surrounding casting.

To guide the cylinder 1 in its movement 80 when contracting or expanding, one of the T-bars 4 is spaced from the cylinder by means of spacing plate 19 which is welded to the bar 4 and to the cylinder 1. The plate 19 is of such width as to leave the space 20 85 between bar 4 and the part 2 of the cylinder opposite the bar. The edge part 3 of the cylinder fits within this space 20, and may move therein when the cylinder contracts or expands. The cylinder 1 is provided 90 with many vents²¹ to allow the escape of gas when the metal is poured and cooling.

In operation the cylinder 1 is first covered with a suitable adhesive loam and this loam may be built up to give varying surfaces as 95 desired, or is equally distributed thereon by rotating the core with respect to a fixed sweep, while the core is supported in suitable bearings at the ends of shafts 12 and 13. Rotation of the core is effected by means of 100 a suitable crank applied at the square end 14 of the shaft 12. In casting, the core is set horizontally or upright and centered within a suitable flask or mold. The metal is then poured around the core and before the metal 105 begins to contract, pin 17 may be removed thus allowing the cylinder 1 to contract and the core to be removed from the mold by a lifting or pulling means applied at the clevis 18. The outward movement of the core 110

bars 9 first causes the toggles 6 to swing around their pivots 5, until the edge 3 of the cylinder 1 engages the filler plate 19 located between and welded to one of the 5 T-bars 4 and the cylinder 1 near its edge 2, then the entire core moves outwardly.

The present invention thus provides an extremely simple contractible core drum requiring little time or labor to prepare it for 10 the mold and to insert and remove it to and from the mold.

Although but one specific embodiment of this invention has been herein shown and described, it will be understood that numerous details of the construction shown may 15 be altered or omitted without departing

from the spirit of this invention as defined by the following claim.

I claim:

A contractible core drum adapted to contract through pressure of a cooling surrounding casting, means normally preventing the contraction of the core drum, said means including a member adapted to make said means ineffective when a predetermined 20 pressure is applied to the drum.

Signed at Chicago this 5th day of May 1913.

OSCAR ONSRUD.
